UNITED STATES PATENT OFFICE.

FAY H. ROSENCRANTS, OF BUSHEY, ENGLAND, ASSIGNOR TO INTERNATIONAL COMBUSTION ENGINEERING CORPORATION, A CORPORATION OF DELAWARE.

FURNACE.

Application filed November 13, 1925. Serial No. 68,783.

This invention relates to furnaces and is particularly useful in connection with furnaces adapted to burn finely divided fuel in suspension, as for example, carburetted oil or pulverized coal and it has for one of its primary objects the provision of improvements with reference to the air supply for combustion to the end that efficiency may be improved and more perfect combustion obtained.

The invention is especially useful as applied to stationary boilers and in this connection it is one of the objects of the invention to burn the fuel with a short hot flame to increase the boiler output while still keeping down the size of the installation.

The foregoing, together with such other objects as may hereinafter appear, or are incident to my invention, are realized by a construction which I have illustrated in preferred form in the accompanying drawing, which is a partial vertical section and side elevation of an oil fed stationary boiler installation embodying my improvements.

Referring now to the drawing, the reference character A denotes the combustion chamber over which is located the boiler B, such boiler being baffled so as to provide three passes a, b, c, the first of which constitutes the outlet for the products of combustion completed within the combustion chamber A.

In normal operation the flue gases pass through the dampers 11, through the breaching 10 and air pre-heater 12, into the flue 8. A bypass 7 controlled by dampers 9 is also provided by virtue of which the gases may be passed direct from the boiler to the main flue rather than through the air preheater.

The air preheater shown is preferably of multiplate type now well understood in this art.

The side walls 13, the rear wall 14 and the bottom 15 of the combustion chamber are hollow, air being taken in at the rear thru the inlet 16 from whence it passes downwardly thru the rear wall to the space beneath the floor. The lower portion of the space within the side walls is divided into vertical compartments d by means of partitions 17, and the air flows from the space below the floor into these compartments rising upwardly thru the side walls and eventually entering the breaching 18; from this breaching the air enters the heater 12 and is

discharged into the combustion space thru the breaching 19. In the present instance an oil burner 20 is located so as to discharge into the lower portion of the combustion chamber and the air is discharged from the breaching 19 around this burner.

The circulation above described is brought about by the fan 21.

The amount of gas passing over the air heater is determined by manipulation of the dampers 9 and 11 by virtue of which as much of the waste gases as desired are caused to pass thru the breaching 10 to the flue 8.

The air in passing downward thru the rear wall, then beneath the floor and then upwardly thru the side walls, absorbs heat and in so doing continues to cool the refractories and extend their life. The air thus preheated is further heated, preferably to a very high temperature, in the air heater 12 and as thus highly heated it is delivered around the burner and mixed with the entering fuel whereby ignition takes place promptly, combustion is completed within a short space of time with a high temperatured flame. In other words, I greatly increase the temperature head thereby by increasing both boiler and furnace efficiency and also increasing the rate of heat absorption by the boiler.

I prefer to use a boiler of smaller size than customary so that the waste gases entering the heater may be higher than usual. By doing so I am enabled to preheat the air to a high degree with the final exit temperatures not unduly high. The increase in temperature head I thus obtain enables me to generate more steam by virtue of the higher rate of absorption incident to the increase in furnace temperature.

It will be obvious that under these conditions the flame will be short and hot and thus both the furnace itself and the boiler may be of comparatively small size as compared with the standard installation intended to deliver the same amount of steam.

It is advantageous to have the side walls hollow all the way up.

What I claim is:

1. In combination, a boiler furnace having hollow rear, side and bottom walls, an offtake, a waste gas air heater, an air inlet in an upper part of the back wall, and breaching communicating with the upper part of the side walls together with means whereby air for

combustion is caused to pass downwardly through the rear wall into the bottom wall, upwardly through the side walls and through the air heater to the combustion space of the furnace.

2. In combination, a boiler furnace having hollow rear, side and bottom walls, the space in the side walls being divided into a plurality of vertically disposed channels communicating at their lower ends with the space in the bottom wall and at their upper ends with a breaching, together with means for causing air for combustion to pass downwardly through said rear wall and into the bottom wall and thence upwardly through said channels and into said breaching.

3. In combination, a boiler furnace having hollow rear, side and bottom walls, a waste gas offtake, a waste gas by-pass having an air heater located therein, and means whereby air for combustion is caused to pass serially

through the rear wall, bottom wall, side walls and air heater.

4. In combination, a boiler furnace having hollow rear, side and bottom walls, a waste gas offtake, a waste gas by-pass having an air heater located therein, and means whereby air for combustion is caused to pass serially through the rear wall, bottom wall, side walls and air heater, said offtake and said by-pass being damper controlled.

5. In combination, a boiler furnace having hollow rear, side and bottom walls, a waste gas air heater, means for controlling the temperature thereof, and means whereby air for combustion is caused to pass serially through the rear wall, bottom wall, side walls and air heater.

In testimony whereof, I have hereunto signed my name.

FAY H. ROSENCRANTS.
